UNITED STATES PATENT OFFICE.

THEODORE H. KRUSE, OF ARVADA, COLORADO, ASSIGNOR OF ONE-HALF TO CLARENCE C. COLE, OF DENVER, COLORADO.

BERRY-PICKER.

1,269,091.

Specification of Letters Patent. Patented June 11, 1918.

Application filed May 22, 1917. Serial No. 170,212.

To all whom it may concern:

Be it known that I, THEODORE H. KRUSE, a citizen of the United States, residing at Arvada, in the county of Jefferson and State 5 of Colorado, have invented a new and useful Berry-Picker, of which the following is a specification.

The subject of this invention is a berry picker wherein gathering fingers are cooperatively associated with a receptacle and the objects of the invention are, first, to provide a picker which will not injure the berries; second, to provide a bag that will protect the berries from thorns; third, to 15 provide a simple and efficient berry picker.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

A practical embodiment of the invention is shown in the accompanying drawing wherein:

Figure 1 is a side elevation of the device, 30 a portion of the handle broken away;

Fig. 2 is a plan view of the same;

Fig. 3 is a vertical central longitudinal section.

Referring to the drawing by numerals:

A handle 1 formed with a reduced end which is surrounded by a sleeve 2, is provided with a longitudinal bore in the reduced end. The extended ends 3 of a ring 4 are adapted to the bore. The ring 4 may

be of any suitable material but is preferably 40 formed of wire. The ring 4 is provided with a series of inclined bores, one of which is indicated at 5 Fig. 3, and the bores are positioned diametrically opposite the extended ends 3, as shown. Fingers 6, preferably of metal, are secured in these bores.

A bag 7 of some puncture resisting material such as leather, is whipped onto the ring 4 by a thread 8 or the like.

The device is used after the manner of 50 the ordinary berry picker of this class. The berries are caught by the fingers 6 and pulled from the bush and drop into the bag 7. The bag 7 being of leather or like material prevents the thorns injuring the picked berries during the operation of gathering further berries. 55

Having described my invention, what I claim as new and desire to secure by Letters Patent, is:

A berry picker, comprising a handle, a ring secured to the handle and having spaced apertures formed therein and extending downwardly and outwardly from the upper face thereof, short prongs secured in the 60 apertures and extending upwardly and inwardly from the ring, and a bag secured within and depending from the ring, the prongs adapted to direct berries downwardly against the ring. 70

In testimony that I claim the foregoing as my own, I have hereto affixed my signature in the presence of two witnesses.

THEODORE H. KRUSE.

Witnesses:

JAMES F. JACOBS,
MARTIN S. SKIFFICH.
